(57) **CLAIM**

We claim the ornamental design of a door latch housing, as shown and described.

DESCRIPTION

FIG. 1 is a front view of a door latch housing.

FIG. 2 is a perspective view of the door latch housing of FIG. 1.

FIG. 3 is a first side view of the door latch housing of FIG. 1.

FIG. 4 is a second side view of the door latch housing of FIG. 1; and,

FIG. 5 is a back view of the door latch housing of FIG. 1. The broken lines in the Figures are for illustrative purposes only and form no part of the claimed design. The shade lines in the Figures show contour or the flatness of a surface, and not surface ornamentation.
